ELECTROMAGNETIC STRUCTURE FOR
CIRCUIT BREAKERS

William M. Scott, Jr., Bryn Mawr, Pa., assignor
to I. T. E. Circuit Breaker Company, Philadelphia, Pa., a corporation of Pennsylvania

Original application January 3, 1941, Serial No. 373,051. Divided and this application May 6, 1944, Serial No. 534,456

1 Claim. (Cl. 200—147)

1

My invention relates in general to the field of circuit interrupters and more specifically concerns a novel and improved form circuit breaker and a control means therefor. This case is a division of my application Serial No. 373,051, filed January 3, 1941, and entitled Circuit interrupter and control therefor.

An object of my invention is to provide a novel circuit breaker in which the electromagnetic winding is split into pluralities of parallel conductors encasing the magnetic coil.

Figure 1 is a fragmentary side view of one of the circuit breaker units illustrating the arc quencher in its raised position.

Figure 2 is a fragmentary cross-sectional view of the magnetic blow out coil taken on line 2—2 of Figure 1.

Referring now to the drawings, an arc quenching unit 45, preferably of the magnetic blow out type, is provided for each of the circuit breaker poles. It is mounted upon the stationary contact and blow out coil assembly which is supported upon the insulated cross-bars 25 by means of metallic blocks 46.

Associated with the arcing chamber is a stationary contact 51 which is engageable by a plurality of complementary movable contacts 52. The details of this structure are more fully described in the parent application referred to above.

The arc quencher 45 as illustrated is of the well known magnetic blow out type. Essentially this structure comprises a pair of parallel insulating plates 202 spaced by end insulating members.

The interior of the arc quencher 45 may have any suitable arc extinguishing construction such as that shown in the parent application.

Mounted upon the sides of the arc quenching structure are a plurality of magnetizable members 213 formed from magnetic laminated material and each communicating with and connected to a central magnetic member 212 by means of the bolts 210 passing through extensions 214. The magnetic members 213 are positioned against the side insulating plates 202 by means of a plurality of straps 215 fastened thereto by the bolts 207.

The entire structure is pivotally mounted, by means of a pair of plates 220, which are secured to the walls of the arc quenching structure upon a shaft 217 which in turn is supported by means of the metallic brace 221.

The magnetic members 211—213 are magneti-

cally energized by means of a coil 216 which is supported upon the insulated cross-bars 25.

The coil 216 is a double turn of copper of rectangular cross-section through which the line current flows. The current enters from the bus bar 226 which is fastened directly to one section 227 of the coil 216. This section 227 passes completely around a rectangular magnetic core 231 and then branches out at 232 into two parallel sections 233 and 234 which again pass around the core 231. Each of these two sections then branches out again at 235 and 236 into two additional sections 237 and 238 and upon completing their half circuit about the core are joined together at 241.

This novel arrangement thus provides the equivalent of two complete turns about the magnetic core 231. The individual turns of the coil are braced by the insulating bolts 243 which pass through aligned perforations 244.

The core 231 is formed from a series of stacked rectangular laminations of some magnetic material such as soft iron clamped together by means of the bolts 251.

These laminations are stacked with their poles to form a U-shaped magnet having the two side members 252 extending from the central core 231. These side members as illustrated come into close frictional contact with the central magnetic structure 212 supported upon the sides of the arcing chamber.

Thus when the arcing chamber is lowered, energization of the core 231 by the line current flowing through the coil 216 will cause the magnetization of all of the members 212, 213 which are strapped to the sides of the arcing chamber to produce a transverse magnetic field across the arc quencher.

The magnetic core 231 is wrapped with an insulating material 253 to preclude the short circuiting of the turns of the coils 216.

The coil 216 terminates in the extension 241, the stationary contact is supported thereupon by means of a plurality of bolts which pass through countersunk perforations therein and engage correspondingly threaded perforations in the extension 241.

A plurality of projections 255 and 256 are provided upon the coil 216 in order to properly position the coil and the attached arcing chamber upon the plate 222.

The material utilized for the coil is preferably a highly conductive one such as copper, the cross-sectional area of which is selected to carry normal load currents at standard temperature rise.

3
The coil is braced to withstand the mechanical stresses imposed thereon by the weight of the arc chute, and those imposed during the flow of fault currents.

I claim:

In a circuit breaker having a pair of cooperable contacts, an arc extinguishing mechanism, an electromagnetic winding for blowing the arc into said arc extinguishing mechanism comprising a metallic conductor, a magnetic core, said metallic conductor encasing said core and thereafter branching into a plurality of parallel conductor sections which encase said core, said parallel sections thereafter branching out into a further plurality of sections and passing around said

core, and reuniting to form a winding section for said core.

WILLIAM M. SCOTT, JR.
